GEAR GRINDING MACHINE

Clarence T. Galloway, Rochester, N. Y., assignor
to Gleason Works, Rochester, N. Y., a corpora-
tion of New York

Application May 10, 1937, Serial No. 141,588

22 Claims. (Cl. 51—52)

The present invention relates to machines for grinding gears and particularly to machines for grinding longitudinally curved tooth gears, such as spiral bevel and hypoid gears.

In spiral bevel and hypoid gear grinding machines in general use, a cupped grinding wheel is used as the grinding tool and this wheel is rotated on its axis and simultaneously swung back and forth to grind the tooth surfaces of the gear.

When it is required to dress the wheel, the operator stops the normal working operations of the machine, the wheel is swung beyond its working path to dressing position, the wheel carrier is unclamped and advanced an amount determined by the wear of the wheel and the amount of stock to be dressed off, then the wheel carrier is reclamped, and the wheel is dressed, and, when the dressing operation is completed, the wheel is returned to working position and the normal operations of the machine restarted. All of the steps embraced in effecting the dressing operation and return of the wheel to working position are effected manually or through manually operated controls. The operations connected with dressing, then, take a considerable time which, in large production shops, means money.

The primary purpose of the present invention is to provide a gear grinding machine which will be fully automatic in its operation, yet but slightly more expensive in construction than machines which are only semi-automatic.

Another object of the invention is to provide a compact, inexpensive control means which may readily be applied to existing semi-automatic gear grinders to make them fully automatic.

With the present invention, a control device is provided that is directly attachable to machines now in general use so that with but slight change, these machines may operate fully automatically. The stopping of the normal working operations of the machine, the movement of the grinding wheel to dressing position, the unclamping of the wheel carrier, the advance of this carrier to compensate for wear and for the stock which is to be dressed off of the wheel, the reclamping of the carrier, the dressing of the wheel, the return of the wheel to operative position and the restarting of the normal working operation of the machine may then all be effected automatically and in proper sequence.

The control device of the present invention comprises a series of cams, all mounted on the same shaft and properly shaped and positioned to effect in the desired order, the various operations described. In the preferred embodiment of

the invention, the cams are driven by a motor forming part of the automatic attachment. When the desired, predetermined number of working operations of the machine are completed, as, for instance, the rough-grinding of all of the teeth of a gear, the automatic stop mechanism of the machine functions to stop the normal working operations and to allow a spring to shift a valve which controls the position of the grinding wheel. When this valve is shifted, the grinding wheel is moved to dressing position and when dressing position is reached, the motor, which drives the series of control cams is started and the cycle of unclamping, advance, and reclamping of the wheel carrier, dressing of the wheel, return of the wheel to working position, and restarting of the normal working operations are all effected automatically. The control mechanism including the drive motor therefor and the series of control cams is compactly housed and can readily be attached to existing grinding machines and the necessary hydraulic and electrical connections can easily be made so that, as stated above, an existing semi-automatic grinding machine may with but little expense be converted into a fully automatic machine.

The automatic control mechanism illustrated in the accompanying drawings is intended specifically for application to spiral bevel and hypoid gear grinding machines of the type described in the copending application of Edward W. Bullock et al., Serial No. 751,738, filed November 6, 1934, now Patent No. 2,099,674, dated November 23, 1937.

In the drawings:

Fig. 1 is a vertical sectional view taken longitudinally through the tool end of a machine of the type illustrated in the Bullock et al. application;

Fig. 2 is a sectional view through this same part of the machine, taken at right angles to the view of Fig. 1, and showing the control mechanism of the present invention in position on the machine and various other parts required in order to effect automatic operation of the machine;

Fig. 3 is a plan-view of the tool end of the machine as modified for automatic operation, the view being on a somewhat reduced scale and parts being broken away for purposes of illustration;

Fig. 4 is a sectional view on the line 4—4 of Fig. 3 but on an enlarged scale;

Fig. 5 is a view of the control box and motor, parts being shown in section and broken away;

Fig. 6 is a section through the control box taken generally on the line 6—6 of Fig. 5;

Fig. 7 is a section taken generally on the line 7—7 of Fig. 6;

5 Fig. 8 is a fragmentary sectional view taken on the line 8—8 of Fig. 7;

Fig. 9 is a diagrammatic view showing, in development, the shapes of the paths of the cams which control the automatic dressing function;

10 Fig. 10 is a fragmentary view showing the lever which controls the position of the valve which governs the position of the grinding wheel and showing, also, the means for moving this lever;

15 Fig. 11 is a section on the line 11—11 of Fig. 3, but on an enlarged scale;

Fig. 12 is a section on the line 12—12 of Fig. 11;

Fig. 13 is a fragmentary elevational view looking at the tool end of the machine; and

20 Fig. 14 is an electrical wiring diagram of the machine.

Reference will now be had to the drawings for a more detailed description of the invention. 20 designates the upright or column of a semi-automatic gear grinder such as described in the Bullock et al. application above mentioned. This upright or column supports the tool mechanism of the grinding machine.

Slidably mounted on the upper face of this upright or column 20 is the tool head 21. The tool head 21 is formed with depending bearing members 22 and 24 which provide a support for an oscillatable and slidable wheel-carrier or quill 25. This wheel carrier or quill 25 is of irregular shape as will be clear from Fig. 1.

35 The column or upright 20 is formed at its forward end with a cylindrically shaped recess 26. There is a cylindrical plate or guard 28 secured to the quill 25 at the front end thereof by screws 29. This plate 28 is adapted to slide back and forth in the recess 26 of the column 20 as the quill feeds back and forth and serves as a guard to prevent entry of grit or dirt into the operating parts of the tool end of the machine.

There is a sleeve 30 secured in an opening in 45 the rear end of the quill 25 by screws 31. This sleeve is mounted for rotating and sliding movement in the bearing 24 and acts to support the quill at its rear end.

There is a ball thrust-bearing 33 mounted in 50 the quill 25 directly behind the cylindrical guide-plate 28. There is a sleeve 34 mounted in this bearing and formed at its rear end with a flange to which a cam-follower 35 is secured by screws 36.

55 The bearing member or arm 22 is formed at its lower end with a semi-cylindrical bearing, as shown in Fig. 2, in which the sleeve 38 is mounted. The sleeve 38 is held in position by the cap-member 40 which is secured to the arm 22 by screws 41. The sleeve 38 is held against axial movement in its bearing by the screw 42 and dowel-pin 43.

The sleeve 38 is slidable in the sleeve 34 but is held against rotation relative to the sleeve 34 by 60 the key 44. This key engages in an elongated key-slot formed internally in the sleeve 34 and is secured by screws to the sleeve 38.

There is a plate 45 secured to the quill 25 by 65 screws 46. This plate has a forwardly projecting pin or stud 47 that is journaled on an anti-friction bearing 48 in the sleeve 38. The forward end of the stud 47 is of reduced diameter and is mounted in a thrust-bearing 49 that is slidably mounted in the sleeve 38. A nipple 50 is threaded 70 in the forward end of the sleeve 38 and between

this nipple and the thrust-bearing 49 is interposed a coil-spring 52.

75 Journaled in the quill 25 with its axis inclined to the axis of the quill is the wheel spindle 55. The cupped grinding wheel W used on the machine is secured in any suitable manner to this spindle. The grinding wheel spindle is driven from a motor (not shown) that is mounted in the base or frame of the machine. The drive is from the motor through a belt 57 to a pulley 58 that is keyed to a hollow shaft 59 which is journaled on anti-friction bearings 60 and 61 in an end-plate 62 which is secured by screws 63 to the upright or column 20.

80 Journaled on anti-friction bearings 65 and 66 in the sleeve 30 is a shaft 68 that has telescoping, splined connection with the hollow shaft 59. Keyed to the shaft 68 is a bevel gear 70 that meshes with another bevel gear 71. The latter gear is keyed to a shaft 72 which is journaled on anti-friction bearings 73 and 74 in a sleeve 75 that is fixedly secured in the quill 25.

85 Keyed to the shaft 72 at its forward end is a pulley 77. This pulley drives a pulley 78, which is secured to the wheel spindle 55, through the belting 79.

90 Through the gearing just described, a rotary motion is imparted to the grinding wheel W to effect grinding rotation.

In a machine of the type referred to, the grinding of the lengthwise tooth surfaces of a spiral bevel or hypoid gear is effected by swinging the wheel back and forth along the length of a tooth of the gear being ground, as the wheel rotates on its axis. The longitudinal swinging movement 95 is effected by oscillating the quill 25. The drive to the quill is from a crank plate 80 (Fig. 2) through a connecting rod 81, an arm 82, a shaft 83 which is connected with the arm 82 through a differential (not shown), a spur gear segment 40 84 which is keyed to the shaft 83, and a spur gear segment 85 which is formed integral with the quill 25. The crank 80 may be driven from any suitable source of power and as it rotates will impart the desired oscillating movement to 45 the quill and to the grinding wheel.

95 In the grinding of a tooth surface of the gear, the rotating and oscillating grinding wheel is fed into full depth engagement with the gear and when the tooth surface has been ground to 50 full depth, the wheel is withdrawn from engagement with the gear and the gear is indexed. The alternate feed and withdrawal movements of the wheel are effected by reciprocating the quill 25 axially.

100 Ordinarily, it is desirable to go around a gear, which is being ground, at least twice, effecting a rough-grinding operation on the first pass around the teeth and producing the finish-grinding operation on the final pass.

Two separate cams are employed to control the feeding movements during rough-grinding and finish-grinding, respectively. These are denoted at 90 and 91, respectively in Fig. 1. These cams are adapted to be engaged selectively with the 105 follower 35 to impart the desired feed movement to the quill 25.

The two cams are integral with one another and are secured to a shaft 93 which is journaled on anti-friction bearings 94 and 95 in a sleeve 70 96. The sleeve 96 is axially reciprocable in the arm or bearing member 22 in order to shift one cam out of engagement with the follower 35 and bring the other cam into engagement therewith.

110 The sleeve 96 is reciprocated by actuation of 75

the spur pinion 98 which meshes with a rack 99 that is integral with the sleeve 96 and is cut into the periphery thereof. In a machine constructed according to the present invention, the pinion 98 is actuated automatically to effect shifting of the feed cam.

The cam-shaft 93 is driven from a shaft 100 (Fig. 3) through the bevel gearing 101, 102, the shaft 103 which is journaled in the tool head 21, the bevel pinion 104 and the bevel gear 105 (Fig. 1). This latter gear is keyed to a sleeve 106 which is journaled on suitable bearings 107 and 108 in a casting 109 and which has a telescoping splined connection with the cam shaft 93.

When it is desired to dress the grinding wheel, it is swung beyond its working path up to dressing position. This is accomplished by movement of the piston 110 (Fig. 2). This piston slides in a cylinder 111 and is secured to a piston-rod 112 which has an adjustable threaded connection with a block 114. The block 114 is secured by screws to a slide 115 that slides in suitable ways formed on the outside of the cylinder 111. There is a rack 116 secured to this slide by screws 117. This rack meshes with a spur gear segment 118 that drives the shaft 83 through the differential already referred to (not shown). When the piston 110 is moved upwardly, then, the quill 25 is swung beyond its normal working path to move the grinding wheel to dressing position.

The dressing mechanism, which is indicated as a whole at D in Fig. 1 may be of any suitable character but preferably is of the same type as described in the Bullock et al. application. It is secured to the column 20 in proper position by T-bolts 120 and 121 (Figs. 1 and 13).

The wheel head 21 is clamped to the column 20 during grinding, but is released and advanced axially of the quill 25, prior to dressing, in order to compensate for wear of the wheel and the amount of stock to be removed from the wheel in the dressing operation. The wheel head is clamped to the column 20 by four spaced T-bolts 122 (Fig. 1) which engage in T-slots 123 formed in the upper face of the column 20.

The stem of each T-bolt is secured to a piston 124 which slides in a bore or recess formed in the wheel head. A coil-spring 125 actuates the T-bolts to released position. The T-bolts are moved to clamping position by hydraulic pressure but are constantly urged to released position by coil-springs 125 one of which is interposed between the top of each piston 124 and a corresponding end-plate 126 which closes the bore in which the piston reciprocates. The end-plates are secured to the wheel-head 21 by screws 127 (Fig. 3).

The positions of the pistons 124 and T-bolts 122 are controlled by a valve 130 which is reciprocably mounted in a bore 131 formed in the wheel-head. The valve 130 is normally urged upwardly to cause the T-bolts to be moved to clamping position by a coil-spring 132 which is interposed between the end of the valve and an end-plate 133. The valve has a stem or stud 135 which projects through an opening in the upper end plate 136 of the cylinder 131. There is a lever 137 pivoted between ears formed on this upper end plate, which can be manipulated to move the valve 130 downwardly against the resistance of the spring 132. The valve 130 is connected by four ducts 138 with the lower ends of the several pistons 124 so that the four pistons 124 are moved together in the same direction when the valve is operated. The valve is connected by an exhaust duct 139 with the sump of the ma-

chine and by a duct 207 with the automatic control mechanism as will hereinafter be described.

To advance the wheel head for dressing the wheel, a screw 140 is provided (Fig. 3). This screw is formed integral with the shaft 141 that is suitably journaled in the wheel head and it threads into a nut 142 which is secured by screws 143 to the upright or column 20.

So far as has been described, the machine illustrated is identical with the semi-automatic machine shown in the Bullock et al. application.

For the purpose of full automatic operation of the machine, a control mechanism made according to the present invention is mounted upon the machine. This control mechanism comprises a motor 150 (Figs. 2 and 5) and a control box or cam housing 151 upon the upper face of which, the motor is mounted.

Journaled on anti-friction bearings 153 and 154 in the cam housing is a shaft 155 to which is keyed seven cams, numbered 157, 158, 159, 160, 161, 162 and 163, respectively.

There is a rod 165 (Figs. 5 and 7) mounted in the housing 151 parallel with the cam shaft 155. Pivotedly mounted on this rod 165 are a series of levers denoted at 167 to 171, respectively, in Fig. 6, all of which are of the same shape as the lever 170 shown in Fig. 7. These levers 167 to 171 inclusive are mounted opposite to and cooperate with the cams 157, 159, 160, 162 and 163, respectively. There is a nose or follower 172 on each lever which engages with the periphery of the cam with which the lever is adapted to cooperate.

Secured by screws 174 to one side of the housing 151 is a valve casing 175. This casing contains the sleeves 177, 178, 179, 180 and 181 in which slide valves 187, 188, 189, 190 and 191, respectively. Into the inner end of each of these valves is threaded a screw or adjustable stop 193 which is adapted to engage that lever, 167, 168, 169, 170 or 171, which is associated with the valve in order to transmit the motion of the lever to the valve.

The valves are held in operative position with the several levers by coil-springs 195. Each coil-spring 195 is interposed between a plug 196 and the outer end of the valve. The plugs 196 thread into a cover-plate 197 which is secured in any suitable manner to the valve casing 175.

The valve 187 controls the movement of the piston 124 (Fig. 1) during the automatic operation of the machine.

Pressure fluid is supplied to the valve 187 through the duct 204 and the ports 202 in the sleeve 177. It is exhausted from the valve chamber through the ports 201 and the duct 200. The valve is connected to the valve 130 (Fig. 1) through the ports 206 in the sleeve 177 and the duct 207.

During automatic operation of the machine the manually operable valve 130 is left in its upper position to which it is normally urged by the coil spring 132. Hence the lines 138, that lead to the several pistons 124, are constantly open to the line 207 that leads to the valve 187. Hence, when the line 207 is on supply, the bolts 122 are held in clamping position and when the line 207 is on exhaust, the bolts are moved to released position. The valve 130 is simply employed, then, when it is desired to manually adjust the wheel head 21. In this case, the lever 137 can be used to push the valve 130 down to put the line 138 on exhaust through the line 139 to unclamp the wheel head and permit its adjustment.

The valve 188 controls the automatic movement of the wheel head. The pressure fluid is supplied to the valve 188 (Fig. 6) through the duct 214 and the ports 212 in the sleeve 178. 5 The duct 214 communicates with the ports 202 in the sleeve 177. The motor fluid is exhausted from the chamber of the valve 188 through the ports 211 of the sleeve 178 and the duct 210 which communicates with the ports 201 of the sleeve 177. This valve 188 is connected through the ports 216 of the sleeve 178 and duct 217 with a cylinder 218 (Fig. 11).

There is a piston 220 mounted to reciprocate in this cylinder and the duct 217 threads into an opening formed in the end-plate 221 of this cylinder. This end plate is secured by screws 222. The piston 220 is constantly urged in one direction by a coil-spring 224 which is mounted in the bore 218 to surround the piston rod 225 20 which is integral with the piston 220.

There are rack teeth 226 formed in one side of the piston rod which mesh with a spur gear segment 227 formed on the periphery of an arm 228 which is journaled on a shaft 229. Keyed to this 25 shaft is a ratchet wheel 230 and pivotally mounted upon the arm 228 is a pawl 232 which is adapted to engage with the teeth of this ratchet wheel to impart motion of the piston 228 to the shaft 229.

30 Keyed to the inner end of the shaft 229 (Fig. 3) is a bevel pinion 234 which meshes with a bevel gear 235 that is keyed to the screw shaft 141. Thus, as the piston 220 moves to the right from the position shown in Fig. 11, it will impart motion to the screw shaft 141 to advance the wheel head 21 on the column 20. The shaft 229 has a square outer end to permit use of a wrench for manual adjustment of the wheel head. Lock-nuts 237 are threaded on a reduced stem-40 like portion 238 of the piston rod 225 to limit movement of the piston rod to the left under actuation of the coil-spring 224. The stem portion 238 of the piston rod slides through an opening in the cover plate 239 which is secured 45 to the housing 240 by screws 241. The housing 240 is secured to a bracket 242 by screws 243 (Fig. 12). This bracket 242 (Fig. 3) is secured in turn to the wheel head 21 by screws 244. To assist in accurate manual adjustment of the wheel head upon the column 20, a dial indicator 245 is provided. This is secured to the shaft 229 by a spring-pressed key 246 (Fig. 12).

The valve 189 controls the positions of the feed-cams 90 and 91 (Fig. 1). This valve is connected to the source of fluid-supply through the ports 250 (Fig. 6) in the sleeve 179 and the duct 251 which communicates with the ports 212 in the sleeve 178. The motive fluid is exhausted from the chamber of this valve 189 either through the ports 254 and duct 255 or through the ports 256 and duct 257. The duct 255 leads into the duct 257 and the latter duct communicates with the ports 211 of the sleeve 178.

The valve 189 is connected by the ports 260 in 65 the sleeve 179 and the duct 261 with a cylinder 262 (Fig. 4). There is a piston 263 reciprocable in this cylinder and the duct 261 leads to one side of this piston through an opening in the end-plate 264 of the cylinder. This end-plate is secured to the cylinder by screws 265. The opposite side of the piston 263 is connected to the valve 189 by a duct 267 which communicates with the ports 268 in the sleeve 179.

The cylinder 262 is mounted upon a bracket 75 270 which is secured by screws 271, (Figs. 3 and

4) to the wheel-head 21. The piston-rod 272 which is connected to the piston 263 carries a rack 274 which meshes with a spur gear segment 275 which is keyed to the shaft 276 to which the pinion 98 (Fig. 1) is secured. Thus, as the valve 189 is shifted back and forth in the sleeve 179 by operation of the cam 160, the shaft 93 (Fig. 1) is moved axially in one direction or the other to shift the roughing and finishing feed cams 90 and 91 alternately into and out of operative position.

The dressing mechanism for the grinding wheel has not been illustrated specifically in the drawings, but this mechanism will be fluid-pressure operated and preferably, as already stated, 1 of the construction described in the Bullock et al. application and shown generally at D in Fig. 1 of the present drawings. The valves 190 and 191 (Fig. 6) control the operation of the dressing mechanism.

The valve 190 is connected to the source of fluid supply through the ports 280 in the sleeve 180 and the duct 281 which communicates with the ports 250 in the sleeve 179. The motive fluid is exhausted from the chamber of the valve 190 either through the ports 282 or the ports 283. The ports 282 communicate with a duct 284 that 25 communicates in turn with the ports 256 of the sleeve 179. The ports 283 communicate with a duct 285 that leads into a duct 286, (Fig. 7). 30 There is a needle-valve 288 which controls the connection of this duct 286 with a duct 290 that in turn communicates with the duct 284. The needle valve 288 threads into the valve casing 175 and can be adjusted to control the rate of 35 flow of the exhaust fluid from the chamber of the valve 190 in one direction of movement of the valve. Thereby the speed of dressing may be regulated to control the fineness of dressing 40 of the grinding wheel.

The valve 190 is connected by the ports 295 and 296 and the ducts 297 and 298, respectively, with the dressing mechanism to actuate the same in opposite directions upon movement of the valve.

The valve 191 is connected to the source of fluid supply by the ports 300 in the sleeve 181 and by the duct 301 which communicates with the ports 280 in the sleeve 180. The motive fluid is exhausted from the chamber of the valve 191 either through the ports 302 or the ports 303. The duct 304 communicates with the ports 282 in the sleeve 180. The ports 303 connect with a duct 305 (Fig. 8). There is a needle valve 307 that controls the connection of this duct with a duct 306 that leads into the exhaust duct 304. The connections are similar to those shown in Fig. 7.

The valve 191 is connected by the ports 309 and 310, respectively, and the ducts 311 and 312, 60 respectively, with the ducts 297 and 298, respectively, which lead to the dressing mechanism so that the dressing mechanism may be actuated in opposite directions upon shift of the valve 191 in opposite directions.

The cam shaft 155 is driven from the motor 150 (Fig. 5) through the bevel gearing 315, 316, the shaft 317, the worm 318 and the worm wheel 319 (Fig. 6). The bevel pinion 315 (Fig. 5) is integral with a shaft 320 that is aligned axially 70 with the armature shaft of the motor 150 and is suitably connected to the same. The bevel gear 316 is keyed to the shaft 317 with which the worm 318 is integral and the worm wheel 319 is keyed to the cam shaft 155.

A solenoid brake mechanism is provided for the motor 150. This may be of any suitable type. As shown, it comprises a solenoid 325 (Figs. 2 and 5) and a brake mechanism designated generally at 326. This solenoid brake is so connected with the controls for starting and stopping the motor 150 that the brake mechanism is released when the motor is started and is thrown on when the motor is stopped. Its purpose is to prevent coasting of the motor drive shaft after the power to the motor is thrown off.

As previously described, the grinding wheel W is moved to and from dressing position by movement of the piston 110 (Fig. 2). The movement of the piston 110 is controlled by a valve 330 which is connected by a pin 331 (Fig. 10) with an arm 332 which is keyed to a shaft 333. There is a lever 334 keyed to the outer end of this shaft. This lever is connected at one end with the solenoid 335. When this solenoid is energized, the lever is swung clockwise about the axis of its shaft 333 to move the valve 330 to the position shown in Fig. 2. A spring-pressed plunger 336 operates on the lever at the opposite side of the shaft 333 to constantly urge the lever in a counterclockwise direction about the axis of its shaft 333.

The valve 330 slides in a sleeve 340 and is connected through radial ports in this sleeve with ducts 341 and 342 which lead, respectively, to opposite sides of the piston 110. The valve 330 is connected by radial ports in the sleeve 340 and a duct 343 with the source of fluid supply and it is connected by radial ports in the sleeve 340 and by the ducts 345 and 346, respectively, with the sump of the machine to permit exhaust of the motive fluid from the valve chamber.

The solenoid 335 is so connected electrically with the feed motor of the grinding machine that when the feed motor is operating, the solenoid is energized. Hence during the grinding operation upon a gear, the solenoid is energized and the valve 330 is held in the position shown in Fig. 2. When the grinding operation is completed, the automatic stop mechanism of the machine, which may be of any usual or suitable construction and is not shown, functions not only to stop the feed motor of the machine but also to break the circuit to the solenoid 335 and thereby deenergize the solenoid.

Mounted upon a plate 350 (Fig. 2) which is secured to the guard 351 of the upright or column 20 are a pair of limit switches 352, 353 and mounted upon the block 114 is a plate 357 that carries spaced trip lugs 354 and 355. The limit switch 352 controls the starting of the motor 150 (Fig. 5). The limit switch 353 controls the starting of the feed motor of the machine. These two limit switches are normally open and they are closed only when the lugs 354 or 355 engage the arms of the switches.

There are two limit switches 360 and 361 (Fig. 5) mounted in the cam housing 151. The limit switch 360 is operated by the cam 161, the roller 65 362 carried by the arm 363 of this switch riding upon the periphery of this cam. The limit switch 361 is operated by the cam 158, the roller 365 carried by the arm 366 of this switch riding upon the periphery of this cam.

The several cams 157, 158, 159, 160, 161, 162 and 163 are suitably shaped to effect in proper order the various functions of the mechanism of the present invention. In the grinding of all gears, it is desirable to dress the grinding wheel 75 between the rough and finish-grinding operations

so as to get a smooth tooth surface for finish-grinding. Sometimes, it is desirable, also, to dress the grinding wheel prior to rough-grinding so that the wheel will be sharp and in good condition to rough-grind. Sometimes it is desirable to make a rough-grinding operation, a semi-finish grinding operation and a final finish-grinding operation in the grinding of a gear and in this event, to dress the wheel between the rough-grinding and semi-finish grinding operations and between the semi-finish grinding and final-finishing operations. The wheel may be used, then, without further dressing to rough-grind the next gear put upon the machine.

It is because of these different possible methods of operation of the machine, and still other methods will suggest themselves to those skilled in the art, that the two cams 162 and 163 and the two valve mechanisms cooperating therewith are provided. One cam and its valve mechanism 15 may be used to control the dressing of the grinding wheel prior to finish-grinding and the other cam and its valve mechanism may be employed to control the dressing of the grinding wheel prior to rough-grinding, or prior to a semi-finish grinding operation. Still further, as stated above, the wheel may be dressed only prior to finish-grinding and may be used without further dressing in the succeeding rough-grinding operations. In this latter case, the wheel is dressed 30 only once for the grinding of each gear and one cam and its valve mechanism does not function at all. This last described modification of the invention is illustrated in the drawings. For this method of operation of the machine, one of the 35 two dressing control members, as, for instance, the member 163 will be simply a circular disc and not a cam and hence it will not impart any motion to the valve 190. Where a disc is used, its diameter will be sufficient to hold the valve, 40 times. The valve 191 is shown in this position in Fig. 6.

The two needle-valves 288 and 301 are provided to control the rates of movement of the 45 diamonds or other dressing elements across the grinding wheel in the dressing operation. The slower a diamond or other dressing tool moves across a grinding wheel during dressing, the better the finish produced on the wheel and the 50 better the finish produced upon the work being ground. For rough and finish-dressing, then, these two needle valves 288 and 301 will be adjusted to permit different rates of flow of the 55 exhaust fluid back to the sump. The needle valve which controls the rate of dressing prior to a rough-grinding operation will be adjusted to provide the wider opening to exhaust so as to permit the freer movement of the dressing mechanism. The valve 301 is illustrated in this 60 position in Fig. 8.

A typical layout of the tracks of the several control cams is illustrated diagrammatically in Fig. 9. In the layout illustrated, the cams are so formed that the cam shaft 155 makes half a 65 revolution between rough-grinding and finish-grinding and half a revolution after the finish-grinding operation is completed and the machine is stopped and the wheel is only dressed prior to finish-grinding. The wheel is not dressed 70 prior to a rough-grinding operation. With this arrangement, the control member 163 will be a plain circular disc, and the control member or cam 162 will have but one lobe, which is denoted at 370 in Fig. 9. This lobe will produce a pass of 75

the dresser across the grinding wheel in one direction, a dwell at the end of the passage, and return of the dresser across the grinding wheel.

- Since it is only necessary to unclamp the wheel head 21 and advance the grinding wheel prior to a dressing operation, the cams 157 and 159 which control the clamping and the movement of the wheel head, respectively, may therefore have only one lobe or recess each. The cam 157 is recessed 10 and its recess is denoted at 371 in Fig. 9. The lobe on the cam 159 is denoted at 372. The three actuating portions, 370, 371 and 372 are so shaped and positioned angularly relative to one another that the wheel head is first unclamped from the column 20, then advanced and then reclamped to the column and then the wheel is dressed. The dwell in the bottom of the recess 371 in the cam 157 is of sufficient length to permit the wheel head to be advanced the desired amount before it is reclamped to the column. The advancing movement of the wheel head is effected, as above described, through the ratchet and pawl mechanism 232-230 (Figs. 11 and 12) which operate the screw shaft 141 (Fig. 25). The resetting of the ratchet and pawl mechanism takes place on the fall of the lobe 372, but since this resetting movement does not affect the position of the screw shaft 141 it can take place before the wheel head is reclamped to the column.

While the wheel head is being advanced, the feed cam-shaft 93 may be shifted axially to shift the feed control cams 90 and 91 (Fig. 1). For the method of operation described, the shaft 35 93 is shifted downwardly after the rough-grinding operation to bring the finishing feed cam 91 into operative engagement with the follower 35. It is shown in this position in Fig. 1. After the finish-grinding operation, when the grinding 40 wheel is again swung up to dressing position, there is no dressing operation and therefore no unclamping or advance of the wheel head, but it is necessary to shift the shaft 93 upwardly again in order to bring the roughing feed cam 45 90 into operative position ready for the rough-grinding operation on the next gear which is put upon the machine.

The cam 160 is formed, therefore, with a recess in its periphery which has a dwell at its bottom of sufficient length that the valve 189 is only moved in one direction during a cycle of operation of the control mechanism. The downward shifting of the shaft 93 takes place while the nose 172 (Fig. 7) of the lever 169 (Fig. 6) is 55 rolling down the slope 373 of this recess and the shift of the cam shaft 93 upwardly takes place while the nose of the lever 169 is travelling up the incline 374 of this recess. The recess is of sufficient peripheral extent so that the cam shaft 60 is shifted downwardly on one operation of the control mechanism and remains in downward position during the ensuing finish-grinding operation of the gear and is only shifted upwardly after the wheel has again been swung to dressing 65 position on the completion of the finish-grinding operation.

To hold the parts as rigidly as possible during the finish-grinding operation, there is a tapered recess 380 provided in the sleeve 96 (Fig. 1) and 70 there is a wedge-shaped member 381 adjustably secured to the bearing 22 by screws 382. This wedge-shaped member fits into the recess 380 so that when the sleeve 96 is moved downwardly, it will hold the sleeve very rigidly.

75 Since for different settings of the needle valves

288 and 307, different periods of time will be required for dressing, it is necessary to stop the motor 150 during dressing and restart it again after the dressing of the wheel is completed. For this purpose, a limit switch 395 (Fig. 13) is mounted on the machine in position to be operated by the dressing mechanism in its movement. This limit switch is incorporated in the electrical circuit to the motor 150 so that when the limit switch is closed, the motor may operate 1 and when the limit switch is opened, the motor is stopped.

In the dressing mechanism illustrated, one side of the grinding wheel is dressed by a diamond that is carried by a swinging arm 396 18 which is moved in opposite directions on the shifting in opposite directions of the valve 190 or the valve 191.

Adjustably secured to this arm are a pair of cam plates 397 and 398 which are fastened to a 20 plate 400 by screws 399 which pass through arcuate slots 401 in the cam-plates. The plate 400 is secured to the arm 396 by screws 402.

The cam plates 397 and 398 have beveled corners 405 and 406, respectively, at their adjacent ends and can be spaced apart any desired distance within the range of adjustment permitted by the length of the slots 401. In effect, then, a recess of any desired length may be provided between the two cam plates and the 30 roller 407 carried by the arm 408 of the limit switch is adapted to ride off of the cam plates into this recess during oscillation of the arm 396.

During the grinding operation, the arm 396 is at one limit of its swinging movement as shown 35 in Fig. 13 and the limit switch is held closed to maintain a circuit to the motor 150. When the grinding wheel is moved to dressing position, the motor 150 is started, as above described, to drive the control cams 157, 158, 159, 160, 161, 40 162 and 163. When the dressing mechanism is actuated by movement of the valve 190 or the valve 191, the arm 396 begins to swing counterclockwise. The roller 407 rides down off the beveled part 405 of the cam-plate 397 and the motor 45 150 is stopped. The needle valve 288 or the needle valve 307 (Fig. 8) controls the rate of swing of the arm 396, that is, the rate of dressing. At the end of the swing of the arm 396, the roller 407 rides up on the cam-plate 398 and the limit switch 395 is again closed and the motor 50 150 restarted. The motor drives the shaft 155 on (Fig. 6) causing the valve 190 or the valve 191 to be reversed. This reverses the direction of movement of the arm 396 and the arm swings 55 back to original position. In this movement, the roller 407 rides down off the cam-plate 398, causing the switch 395 to be opened and again stopping the motor 150, and at the end of the movement, the roller rides up onto the cam plate 60 397, restarting the motor 150. The motor then drives the cam shaft 155 on to complete the cycle 65 of operations of the control mechanism.

By providing the limit switch 395, then, the motor 150 is stopped long enough to permit of dressing the wheel to the desired fineness without upsetting the time-cycle of the whole control mechanism.

After the dressing operation is finished, the grinding wheel is returned to operating position. 70 This is done by energizing the solenoid 335 (Figs. 2 and 10) which causes the valve 330, the piston 110 and the quill 25 to be moved to the positions shown respectively in Fig. 2. The cam 158 is provided with a lobe 385 to effect operation of 75

the limit-switch 361 to cause the solenoid 335 to be energized at the proper time. When the piston 110 has returned to the position shown in Fig. 2, the lug 355 strikes the arm of the limit-switch 353 and closes this switch to start the feed motor of the machine. The solenoid 335 is so connected with this feed motor, as already described, that it remains energized as long as the feed motor is in operation and hence holds the valve 330 in the position shown in Fig. 2 during grinding. Therefore, when the roller 365 (Fig. 5) of the arm 366 of the limit-switch 361 rides down off of the lobe 285 of the cam 158, the solenoid 335 is not deenergized and the piston 110 does not move upwardly.

When the quill 25 and the grinding wheel have again returned to operative position, the controller motor 150 (Fig. 5) is stopped. This is done by operating the limit-switch 360. There are two lobes 386 and 387 provided on the cam 161 to operate this limit switch. One trips the switch at the end of the finish-dressing cycle after the grinding wheel has been returned to grinding position ready for the finish-grinding operation and the other trips the switch at the end of the second operation of the controlling mechanism after the grinding wheel has returned to grinding position ready for rough-grinding a new gear.

The dotted line 390 has been drawn across the path of the several cams in Fig. 9. As has already been stated, in the embodiment illustrated in Fig. 9, the cam shaft 155 makes only half a revolution during an operation of the control mechanism. The parts of the cam path to the left of the line 390 are in operation during the first cycle of operation of the control mechanism, that is, between the rough and finish-grinding operations and the parts of the cam path to the right of this line are in operation during the second cycle of operation of the control mechanism between the finish-grinding and rough-grinding operations of the machine.

One way in which the machine may be wired electrically to accomplish the desired functions is illustrated diagrammatically in Fig. 14. 410 denotes the feed motor, while the motor which operates the automatic control mechanism is again designated at 150. The automatic stop mechanism of the machine is denoted at 412.

A start button 411 is provided at some convenient point on the machine. When this start button 411 is pressed in, a circuit is made from the main line L₁ through the line 414, the automatic stop 412, which is at this time closed, the lines 433 and 469, the start button 411, the line 415 and the coil 416 of a standard control 418 to the main line L₂. This energizes the coil 416 and pulls in the switch arms 420, 421, 422 and 423, thereby closing the circuit from the main lines L₁, L₂ and L₃ to the feed motor 410 and starting this motor.

When the switch arm 420 is closed, the solenoid 335 is energized, the circuit to this solenoid being made from the main line L₁ through the switch arm 420, the line 425, the solenoid coil 335, the line 426, the line 427 of a standard relay 428, and the line 429 to the main line L₂. The solenoid, when energized, operates to hold the lever 334 in the position shown in Figs. 14 and 2 to hold the valve 330 in the position shown in Fig. 2.

The start button 411 is, as usual, a normally open button and when it is released by the operator, it flies open. The circuit to the solenoid 335 and the controller coil 416 is maintained,

however, through the normally closed stop button 430. This circuit is from the main line L₂ through the coil 416, the switch arm 423, the line 432, the stop button 430, the line 433, the automatic stop 412, and the line 414 to the main line L₁.

When the automatic stop mechanism 412 is tripped, at the end of a series of grinding operations on a gear, as above described, the coil 416 and solenoid 335 are deenergized. Thus, the feed motor 410 is stopped and the spring pressed plunger 336 is able to shift the valve 330 (Fig. 2). This causes the piston 110 (Fig. 2) to be shifted upwardly to swing the grinding wheel to dressing position. At the end of the up-stroke of the piston 110, when the grinding wheel is in dressing position, the lug 354 (Fig. 2) will close the normally open limit switch 352. This will close a circuit to the coil 435 of the relay 428, energizing this coil. The circuit is from the main line L₁ through the line 436, the limit switch 352, the line 437, the coil 435 and the line 429 to the main line L₂. When the coil 435 is energized, the switch arms 440 and 441 of the relay 428 will be closed. This will close the circuit to the coil 443 of the standard controller 445, the circuit being made from the main line L₂ through the line 446, the coil 443, the line 447, the switch arms 441 and 440 of relay 428, the line 448, the limit switch 395, which is at this time closed, the line 449, the line 450, the line 451 and the line 436 to the main line L₁.

When the coil 443 is energized, the switch arms 455, 456 and 457 will be closed, thus closing the circuit to the control motor 150 from the main lines L₁, L₂ and L₃ and starting this motor. The motor 150 drives the control cams, as already described. The control cams, as already described, govern the clamping and unclamping, and the shifting of the wheel head, and the operation of the wheel-dressing mechanism.

As the dressing mechanism swings across the grinding wheel, the limit switch 395, (Figs. 13 and 14) will be allowed to open when the roller 407 drops off of the plate 397 or the plate 398, as above described. When the limit switch 395 opens, it breaks the circuit to the feed motor 150 and the feed motor is stopped. When the roller again rides up on one of the plates 397 or 398, this circuit is again made, however, and the control drive motor 150 is again started.

When, in the course of operation of the control mechanism, the control cam 161 closes the normally open limit switch 361 (Figs. 5 and 14), a circuit is again made to the solenoid 335 and this solenoid is energized to shift the valve 330 back to the position shown in Fig. 2 and return the grinding wheel to operative position. The circuit is from the main line L₁ through the line 436, the line 451, the limit switch 361, the line 460, the solenoid coil 335, and the lines 426, 427 and 429 to the main line L₂.

When the piston 110 moves downwardly in its cylinder (Fig. 2), the lug 354 moves away from the arm of the limit switch 352 and this limit switch flies open, deenergizing the coil 435 of the relay 428. The control motor 150 continues to run, however, until the cam 158 (Fig. 5) closes the normally open limit switch 360 (Figs. 5 and 14). Then a coil 465 of the relay 428 is energized and this pulls the switch arms 440 and 441 open, breaking the circuit to the coil 443 of the controller 445 and allowing the switch arms 455, 456 and 457 to drop open. The circuit to the coil 465 is from the main line L₁ through the line 75

436, line 451, the line 450, the line 466, the coil 465, the lines 427 and 429 to the main line L₂.

The diamond dresser stops at one end of its swing and the normally open limit switch 395 is therefore held closed. When the piston 110 is returning to the position shown in Fig. 2, the normally open limit switch 353 is closed by the lug 355. The automatic stop 412 is of the construction that closes immediately after it is opened so that it is closed at the moment. A circuit is therefore made from the main line L₂ through the coil 416, line 415, limit switch 353, line 468, line 469, line 433, automatic stop 412 and line 414 to the main line L₄, energizing the coil 416 of the controller 418. This therefore causes the feed motor 410 to be restarted as above described and the machine again goes through a grinding cycle. Then the feed motor is stopped and the grinding wheel is swung to dressing position. When the wheel reaches dressing position, the control motor 150 is again started as before.

The cam 158 (Figs. 5 and 9) is so shaped, as above described, that it will close the limit switch 361 only on the first half revolution of the cam. On the second half revolution of the cam, the limit switch remains open, the solenoid 335 is not energized to return the grinding wheel to operating position and the machine is stopped with the grinding wheel in dressing position. To resume grinding, then, it is necessary for the operator to again press in the start button 411.

The principles of the present invention will be understood from the preceding description but 35 may be summed up briefly here.

We shall assume that the parts are in the positions shown in Fig. 1. The operator starts the machine by pressing the start button 411 that starts the feed motor 410. The rotating grinding wheel then commences to swing about the axis of the quill 25 and to feed into full depth engagement with the gear under actuation of that feed cam which is in engagement with the follower 35 (Fig. 1), in the first instance, the 40 roughing feed-cam 90. When a tooth surface or tooth surfaces of the gear have been ground, the wheel is withdrawn and the gear is indexed. Then the rotating and swinging wheel is fed back into engagement with the gear and another tooth 45 surface or pair of tooth surfaces of the gear are ground. The alternate grinding and indexing proceeds until all of the teeth of the gear have been rough-ground, when the automatic stop mechanism 412 of the machine functions. This 50 stops the feed motor 410 of the machine, but not the wheel drive motor. The stopping of the feed motor causes the shaft 93 to be stopped and stops the crank 80 which oscillates the quill 25. The stoppage of the feed motor also causes the solenoid 335 to be deenergized. The spring-pressed 55 plunger 336 then operates to shift the lever 334 (Figs. 2 and 10) in a counter-clockwise direction about the axis of the shaft 333 and the valve 330 is moved downwardly and the piston 110 upwardly. This causes the quill 25 to swing upwardly 60 and move the grinding wheel out of its working path to dressing position. When the lug 354 (Fig. 2) on the block 114 strikes the arm of the limit-switch 352, the control drive motor 150 is started.

This imparts rotation to the cam shaft 155 (Figs. 6 and 9). As this shaft rotates, the nose 172 (Fig. 7) on the arm 167 (Fig. 5) rides down into the recess 371 (Fig. 9) of the cam 157, 75 allowing the valve 187 to move to the position

shown in Fig. 6 under actuation of its spring 195. This puts the line 207 (Fig. 1) on exhaust and allows the coil springs 125 to move the T-bolts 122 to released position. Then the lobe 372 of the cam 159 operates to shift the valve 188 downwardly from the position shown in Fig. 6 to cause the piston 220 to be moved to the right to the position shown in Fig. 11, causing the screw-shaft 141 to be rotated to advance the wheel head 21. Simultaneously the nose of the lever 169 rides down the side 373 (Fig. 9) of the recess 375 in the cam 160, allowing the valve 189 to move upwardly under actuation of the spring 195. This puts the line 261 on supply (Fig. 4) and through the gearing 274, 275, 98, 99 (Fig. 1) moves the sleeve 96 and shaft 93 downwardly to bring the finishing feed cam 91 into the position shown in Fig. 1. Then the cam 157 causes movement of the valve 187 downwardly from the position shown in Fig. 6 and the line 207 (Fig. 1) is put on supply to reclamp the wheel head 21 to the column 20. At approximately the same time, the cam 159 permits the valve 188 to return to the position shown in Fig. 6 and the line 217 (Fig. 11) is put on exhaust, permitting resetting of the pawl and ratchet mechanism 232-230. Then the cam 162 shifts the valve 190 downwardly from the position shown in Fig. 6 to cause the dressing mechanism to be actuated. As the dressing mechanism starts its movement, the roller 407 (Fig. 13) of the limit switch 395 drops off the cam-plate 397 and the motor 150 is stopped. The dressing mechanism continues on to the end of its movement, however. The rate of dressing is governed by the setting of the needle valve 288 (Fig. 8). At the end of travel of the dressing mechanism, the limit-switch 395 is again closed and the motor 150 is restarted. This drives the cam 162 on to permit the valve 190 to be shifted back to the position shown in Fig. 7 under actuation of the spring 195. This reverses the direction of movement of the dressing mechanism and the parts return to original position. During this return movement, the motor 150 is again stopped by operation of the limit switch 395 and at the end of this return movement is again started. The cam 158 then trips the limit-switch 361 to energize the solenoid 335. This causes the valve 330, piston 110 and quill 25 to be returned to the position shown in Fig. 2. When the lug 355 strikes the arm of the limit-switch 353, the feed motor restarts and the grinding wheel begins again to swing about the axis of the quill 25 and to feed into the gear to effect the finish-grinding operation upon the tooth surfaces of the same. Just prior to the restarting of the feed motor, the controller motor 150 is stopped by operation of the cam 161, the lug 386 on this cam operating the limit-switch 360.

After all of the teeth of the gear have been 60 finish-ground, the automatic stop mechanism 412 again functions to stop the feed motor 410 and the solenoid 335 is again deenergized. Then the valve 330 is again shifted downwardly and the piston 110 again moved upwardly to move 65 the quill 25 and the grinding wheel to dressing position. When the grinding wheel has reached dressing position, the trip-lug 354 again trips the limit switch 352 to again start the control motor 150. With the layout of the cams illustrated in 70 Fig. 9, however, the only operation which takes place is shifting of the valve 189 back to the position shown in Fig. 6 by operation of the cam 160, causing the piston 263 (Fig. 4) to be moved back to the position shown in Fig. 4 and the 75

sleeve 96 and shaft 93 to be moved upwardly from the position shown in Fig. 1, to bring the roughing feed cam 90 into operative engagement with the follower 35.

This time, there is no unclamping of the wheel head, no advance of the wheel head, and no dressing of the grinding wheel because with the described method of operation of the machine, the wheel is not dressed prior to a rough-grinding operation. Moreover, this time the cam 158 does not close the limit switch 361. Hence, this time, the solenoid 335 is not energized and the grinding wheel is not returned to operating position.

Just prior to the time that the cam shaft 155 completes a revolution, the cam 161 operates through its lobe 387 to trip the limit-switch 360 again and stop the controller motor 150. Since the feed motor of the machine is already stopped, only the grinding wheel continues running. It simply rotates idly in dressing position until the operator has removed the gear which has been ground and chucks a new gear. Then he restarts the feed motor, causing the grinding wheel to be swung back to operating position and begin the grinding operation upon the new work piece.

While the invention has been described in connection with a machine for grinding longitudinally curved tooth gears with a particular type of grinding wheel and particular motions thereof, it will be understood that the mechanism of the invention may be employed, with suitable modification, to operate automatically any machine for grinding gears regardless of type and regardless of the form or motion of the grinding wheel. In general it may be said that while the invention has been described in connection with a particular embodiment thereof, it will be understood that it is capable of further modification and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. In a machine for grinding gears, a grinding wheel, means for actuating the wheel to effect the grinding operation, means for moving the grinding wheel from working position to dressing position and back, dressing mechanism, a motor, means operatively connecting said motor to said dressing mechanism to operate the same on actuation of the motor, means operative when the grinding wheel reaches dressing position to start said motor, and means operative when the grinding wheel has been returned to operative position, to stop said motor.

2. In a machine for grinding gears, a grinding wheel, means for actuating the grinding wheel to effect the grinding operation, a fluid-pressure operated piston for moving the grinding wheel from operative to dressing position and back, dressing mechanism, means for actuating the dressing mechanism, limit-switches adapted to be operated at opposite ends of the travel of the piston to start the means for actuating the dressing mechanism and to start the means for actuating the grinding wheel, respectively,

means for causing said piston to move the grinding wheel to dressing position when a grinding operation has been performed on all of the teeth of a gear, and means for causing said piston to return the wheel to operative position after the wheel has been dressed.

3. In a machine for grinding gears, dressing mechanism, fluid-pressure operated means for actuating said dressing mechanism, a pair of reverse valves, either of which is adapted to control the direction of movement of said dressing mechanism, a valve associated with each of said valves to predetermine the rate of dressing during operation of the corresponding reverse valve, and separate means for controlling the operation of each reverse valve.

4. In a machine for grinding gears, a grinding wheel, means for actuating the grinding wheel to effect the grinding operation, means for moving the grinding wheel from operative to dressing position and return, dressing mechanism, fluid-pressure operated means for actuating said dressing mechanism, a pair of reverse valves either of which is adapted to control the direction of movement of the dressing mechanism, a valve associated with each of said reverse valves to predetermine the rate of dressing, said last named valves being separately adjustable so that the dressing of the wheel may take place at one rate when one of the reverse valves is in operation and at a different rate when the other reverse valve is in operation, a control member for controlling the movement of each reverse valve, said control members being mounted on the same shaft, and means for rotating said shaft through a part of a revolution each time the grinding wheel is moved to dressing position.

5. In a machine for grinding gears, a grinding wheel, means for actuating the grinding wheel to effect the grinding operation, means for moving the grinding wheel from operative to dressing position, dressing mechanism, a cam for controlling the operation of the dressing mechanism, and means for imparting a step-by-step movement to the cam each time the grinding wheel is moved to dressing position.

6. In a machine for grinding gears, a frame, a support slidable on the frame, a grinding wheel journaled in the support, means for clamping the support to the frame during the grinding operation, dressing mechanism, means for moving the grinding wheel from operating to dressing position, means for actuating said clamping means to move the same to or from operative position, means operable to advance said support with reference to said dressing mechanism, when the support is unclamped, to compensate for wear of the wheel, means operable to actuate said dressing mechanism, control mechanism for clamping, advancing and dressing mechanisms, and means for imparting step-by-step movement to the control mechanism each time the grinding wheel is moved to dressing position.

7. In a machine for grinding gears, a frame, a support slidable on the frame, a grinding wheel journaled in the support, means for clamping the support to the frame during the grinding operation, dressing mechanism, means for moving the grinding wheel from operating to dressing position, means operable to advance said support with reference to the dressing mechanism when it is unclamped, to compensate for wear of the grinding wheel, a series of cams for controlling the dressing, advance and clamp-

- ing mechanisms, a shaft to which all of said cams are secured, and means for rotating said shaft through a part of a revolution each time the grinding wheel is moved to dressing position.
5. 8. In a machine for grinding gears, a grinding wheel, means for imparting grinding movement to the grinding wheel, separate cams selectively operable to control the relative rate of feed movement of the grinding wheel into the 10 gear for rough and finish-grinding, respectively, dressing mechanism, means for moving the grinding wheel from operating to dressing position and means operable on successive movements of the grinding wheel to dressing position 15 to move the two feed cams alternately into operative position.
9. In a machine for grinding gears, a grinding wheel, dressing mechanism, a frame, a tool support on which the wheel is mounted and 20 which is movable on the frame to advance the wheel into the dressing mechanism to compensate for wear of the wheel, means for clamping the tool support to the frame, means for moving the wheel from grinding to dressing position, and separate motor driven means mounted on the machine and operable, when the wheel is in dressing position, to release said support, advance the same, reclamp the support to the frame, and then actuate the dressing mechanism.
- 25 10. In a machine for grinding gears, the combination with a grinding wheel, means for rotating the wheel, means for producing a relative feed movement between the wheel and the work to effect grinding of the tooth surfaces of a gear to the desired depth, and means for stopping the feed mechanism when a predetermined number of grinding operations have been performed on the work, of means operable to move the wheel to dressing position when the feed mechanism is stopped, separate motor driven means operable, when the wheel is in dressing position, to effect dressing of the wheel and means operable, when dressing is completed, to 30 return the wheel to operative position, restart the feed mechanism and stop the separate motor.
11. An attachment for a gear grinding machine having fluid-pressure operated dressing mechanism comprising a motor, a reverse valve for controlling the direction of movement of the dressing mechanism, a separate valve for controlling the rate of dressing, means adapted to be driven by the motor for actuating said reverse valve, and means for operatively connecting the reverse valve to said dressing mechanism.
- 35 12. An attachment for a gear grinding machine having separate means for controlling the feed of the grinding wheel during rough and finish-grinding operations, respectively, fluid-pressure operated means for bringing the two control means alternately into operative position, and fluid-pressure operated dressing mechanism, comprising a motor, reverse valves for controlling the direction of movement of the dressing mechanism and the shifting of the feed control means, respectively, and means adapted to be driven by said motor for actuating said reverse valves, and means operatively connecting the reverse valves, respectively, with the dressing mechanism and the means for shifting the feed control means.
- 40 13. An attachment for a gear grinding machine which has a frame, a grinding wheel, a dressing mechanism therefor, a wheel support on which the wheel is mounted that is movable on the frame to advance the wheel into the dressing 45 mechanism to compensate for wear of the wheel, fluid pressure operated means for moving said tool support, fluid pressure operated means for clamping the support in grinding position, and fluid-pressure operated means for moving the grinding wheel from grinding to dressing position and back, comprising a motor adapted to be mounted upon the machine, valves controlling, respectively, the operation of the dressing mechanism, the movement of the wheel support and the clamping of the same, means driven by said motor for actuating said valves in timed relation, and means operatively connecting the valves with the parts controlled thereby.
14. An attachment for a gear grinding machine which has means for dressing the grinding wheel and means for advancing the wheel relative to the dressing mechanism to compensate for wear, said attachment comprising a plurality of cams that are adapted to be connected operatively to the two named means to operate them in timed relation, and means for actuating said cams.
15. An attachment for a gear grinding machine which has means for dressing the grinding wheel, means for advancing the wheel relative to the dressing mechanism to compensate for wear, and means for securing the wheel in any position to which it is advanced, said means being releasable to permit advance of the wheel, said attachment comprising a plurality of cams that are adapted to be connected operatively to the three named means to operate them in timed relation, and means for actuating said cams.
16. An attachment for a gear grinding machine which has means for dressing the grinding wheel, means for advancing the wheel relative to the dressing mechanism to compensate for wear, means for securing the wheel in any position to which it is advanced, a pair of feed cams for governing the feed of the grinding wheel into the work during rough and finish grinding, respectively, and means for shifting the feed cams to move them alternately into operative position, said attachment comprising a plurality of cams that are adapted to be connected operatively to the four named means to operate said means in timed relation, and means for actuating said cams.
17. An attachment for a gear grinding machine which is provided with means for moving the grinding wheel from grinding to dressing position, means for dressing the grinding wheel, and means for advancing the wheel relative to the dressing mechanism to compensate for wear, said attachment comprising a plurality of cams that are adapted to be connected operatively to the two last named means to operate them in timed relation, and means adapted to be actuated, when said grinding wheel is moved to dressing position, to actuate said cams.
18. An attachment for a gear grinding machine which has a grinding wheel, means for moving the wheel automatically from grinding to dressing position when a predetermined number of operations on the gear have been completed, means for dressing the grinding wheel, and means for advancing the wheel relative to the dressing mechanism to compensate for wear, said attachment comprising a plurality of control members that are adapted to be connected operatively to the two last named means, respectively, to operate them in timed relation, and means adapted to be actuated when said grinding

wheel is moved to dressing position to actuate said control members.

19. An attachment for a gear grinding machine which has a grinding wheel, means for moving the grinding wheel automatically from grinding to dressing position when a predetermined number of operations on the gear have been completed, means for dressing the grinding wheel, means for advancing the wheel relative to the dressing mechanism to compensate for wear, and means for securing the wheel in any position to which it is advanced, said means being releasable to permit advance of the wheel, said attachment comprising a plurality of control members that are adapted to be connected operatively to the dressing, advancing and clamping means, respectively, to operate them in timed relation, and means adapted to be actuated when said grinding wheel is moved to dressing position to actuate said control members.

20. An attachment for a gear grinding machine which is provided with a grinding wheel, with means for moving the grinding wheel from grinding to dressing position, means for dressing the grinding wheel, and means for advancing the wheel relative to the dressing mechanism to compensate for wear, said attachment comprising a motor, means operatively connecting the motor with the two last-named means to operate them in timed relation on actuation of the motor, and means adapted to be actuated, when said grinding wheel is moved to dressing position, to start said motor.

21. In a machine for grinding gears, a grinding wheel, means for moving the grinding wheel from operative to dressing position and back, means for actuating said first named means to

cause the wheel to be moved to dressing position after a predetermined number of operations have been completed on a gear, dressing mechanism, fluid pressure operated means for actuating said dressing mechanism, a reverse valve controlling the direction of movement of the dressing mechanism, two control members, means operatively connecting one of said members to the reverse valve to shift said valve alternately in opposite directions, means operatively connecting the other member to the first-named means to cause the grinding wheel to be returned to grinding position, adjustable valves for controlling the rate of movement of the dressing mechanism during dressing, means for actuating the control members, and means for stopping the last named means during dressing and for restarting it again.

22. In a machine for grinding gears, a grinding wheel, means for moving the grinding wheel from operative to dressing position, actuating means, dressing mechanism, means for operating the dressing mechanism, means actuatable by said actuating means for controlling the direction of movement of the dressing mechanism, means actuatable in timed relation with said control means for causing return of the grinding wheel to operative position, means for starting the actuating means when the grinding wheel reaches dressing position and means for stopping the actuating means when the grinding wheel returns to operative position, adjustable means for controlling the rate of movement of the dressing mechanism during dressing, and means controlled by movement of the dressing mechanism in either direction to stop and restart said actuating means.
